SCAFFOLD BRACKET ANCHOR
Joseph A. Fortin, Sr., Somerset, Mass.
(48 Winter St., Fall River, Mass. 02720)
Filed June 28, 1965, Ser. No. 467,305
6 Claims. (Cl. 248—235)

ABSTRACT OF THE DISCLOSURE

A lightweight anchor to bridge spaced studs of a building structure which anchor is channel shape and reinforced.

This invention relates to scaffolding such as is used by builders to operate on the side of a building.

Heretofore the scaffold bracket which engaged the outer siding of the building was anchored in place by a rod extending through the siding and passing through a wooden 2" x 6" which extended across between studs on the inner side of the building. Such a 2" x 6" was heavy and cumbersome, wore easily and had to be discarded early in its use because it would not withstand many turnings of the nut which engaged it to hold the rod of the scaffold bracket in place.

This invention comprises an improvement in such anchor which improvement is fabricated of sheet stock in a structurally strong manner from metal and is lighter in weight than the solid wooden 2 x 6's heretofore used. It is further supported in its portion placed in tension and by reason of its material is of much greater wear resistance than heretofore.

One of the objects of the invention is to provide a lightweight anchor for a scaffold bracket.

Another object of the invention is to provide an anchor which will afford relatively easy turning of the nut which engages it to hold the bracket in place.

Another object of the invention is to so construct the bracket that it will be resistant to the forces which are applied on it to hold the bracket in place.

Another object of the invention is to provide a structure which will be long lasting and which will withstand the wear to which it is subjected.

With these and other objects in view, the invention consists of certain novel features of construction as will be more fully described and particularly pointed out in the appended claims.

In the accompanying drawings:

FIG. 1 is a side elevation of the scaffold bracket showing the same as engaging the side of a building illustrated fragmentally in section and with the anchor of this invention in place;

FIG. 2 is a sectional view centrally longitudinally through the anchor showing a fragmental portion thereof;

FIGS. 3 and 4 are sections on lines 3—3 and 4—4 of FIG. 2;

FIG. 5 is a central sectional view showing the tension rod as partly removed from the anchor; and

FIG. 6 is a top plan view through the building structure showing the anchor as engaging the spaced studs thereof.

The fragmental portion of the building comprises a siding 10 with vertical studs 11 supporting the siding. The scaffold bracket designated generally 12 comprises a horizontal arm 14 of generally L-shape having a horizontal portion 15 and a strengthening vertical rib 16. The horizontal portion 15 is provided with a plurality of openings through any one of which the upstanding end 17 of the rod 18 may be positioned and held by means of a cotter pin 19. This rod extends through a face plate 20 at the end of the arm 14 and thence through a hole

2

in the siding 10 to engage the anchor 30 which is the subject of this invention. This arm 14 is also equipped with a leg 21 pivotally attached to the vertical portion 16 and comprising two parts pivoted together as at 22 and extending to and pivoted to a diagonal brace 23 as at 24, this brace also being pivoted at its other end to the arm 14 as at 25. This brace 23 may be L shaped with portions 26 and 27 for mutually stiffening each other.

The anchor 30 comprises spaced side walls 31 with the widest portion at midway of their length. From this widest portion these arms taper to their ends at the narrow portion 33 along one edge while the arms are perfectly straight as at 34 along their stud engaging edge. A bridging wall 35 extends along the tapering portions of the side walls and is welded thereto as at 36 and is turned downwardly at its ends as at 37 and there welded to the ends of the side walls 31 as at 38, thus providing a generally channel shaped structure of tapering shape with straight edges 34 along one edge thereof. This structure is further reinforced by webs 39 at spaced locations usually disposed about halfway between the mid portion of the length of the side walls and their ends. A block 40 which may be tapered as shown in FIGS. 2 and 5 is located at the mid portion of this anchor and extends from side wall to side wall and there welded. A plate 43 is on the outer surface of the bridging wall 35 at the location of the block 40. A hole 41 extends through the plate 43, the bridging wall 35 and through the block centrally widthwise thereof so as to provide an opening through which the rod 18 threaded as at 42 may extend.

This anchor is reinforced further by tension rods 45 which are located in grooves 46 in the webs 39 and also located in grooves 47 in the block 40. This tension rod is hook shaped as at 48 at its ends through which hook pins 49 extend into the side walls 31, thus securing the tension rod 45 from the ends of the side wall across the webs and block in a manner such that a triangular relationship is provided. Thus, through the shape of the edge of the side walls which are tapered and provide a triangulation we also have a second triangulation of the tension rod 45 with the side walls. It will thus be apparent that when a nut 50 is screwed onto the threads 42 of the rod 18 and pressure is brought to bear centrally of the anchor toward the siding which is resisted by the studs 11 which are engaged by the end portions of the anchor, the part of the anchor adjacent the straight edge 34 is placed in tension as there is a tendency to stretch the edge 34 of the side wall 31, and this would be resisted by the rod 45 which is in tension. In this manner the anchor could not readily bend being well supported. Further the tapering of the anchor permits the handle 51 of the nut 50 to be more easily rotated on the threaded rod by affording greater clearance as such action takes place.

I claim:

1. A scaffold bracket comprising a horizontal arm to project from the siding of a building and a vertical leg to extend downwardly therefrom along the outer surface of a building there being a juncture of said arm and leg, a rod having a threaded free end extending from a location adjacent the juncture of said arm and leg for passing through a siding of the building between spaced studs on the inner surface of the building and an anchor of length to extend from stud to stud of the building and having an opening through which said rod extends, a nut on said rod to force the anchor against the building studs and draw the bracket against the outer surface of the siding, said anchor comprising a channel member having spaced side walls and a spanning bridging wall extending from end to end thereof, said side walls having the widest lateral dimension adjacent the center thereof and tapering from the mid portion toward each end, a

block at the center portion of said anchor with a hole therethrough receiving said bracket rod and spaced webs extending between said side wal's.

2. A scaffold bracket comprising a horizontal arm to project from the siding of a building and a vertical leg to extend downwardly therefrom along the outer surface of a building there being a juncture of said arm and leg, a rod having a threaded free end extending from a location adjacent the juncture of said arm and leg for passing through a siding of the building between spaced studs on the inner surface of the building and an anchor of length to extend from stud to stud of the building and having an opening through which said rod extends, a nut on said rod to force the anchor against the building studs and draw the bracket against the outer surface of the siding, 10 said anchor comprising a channel member having spaced side walls and a spanning bridging wall extending from end to end thereof, said side walls having the widest lateral dimension adjacent the center thereof and tapering from the mid portion toward each end, a block at the center portion of said anchor with a hole therethrough receiving said bracket rod and a tension rod attached to said side walls adjacent their ends and extending across said block.

3. A scaffold bracket as in claim 2 with spaced webs 25 extending between said side walls, said tension rod also extending across said webs at an opposite angle to the angle line of said anchor to the taper of said side walls.

4. An anchor for a scaffold bracket of length to extend from stud to stud of a building and having an opening 30 through which a bracket rod may extend, said anchor comprising a channel member having spaced side walls

and a spanning bridging wall extending from end to end, said side walls having the widest lateral dimension adjacent the center thereof and tapering from the mid portion toward each end, a block at the center portion of said anchor with a hole therethrough for a bracket rod and spaced webs extending between said side walls.

5. An anchor for a scaffold bracket of length to extend from stud to stud of a building and having an opening through which a bracket rod may extend, 10 said anchor comprising a channel member having spaced side walls and a spanning bridging wall extending from end to end, said side walls having the widest lateral dimension adjacent the center thereof and tapering from the mid portion toward each end, a block at the center portion of said anchor with a hole therethrough for a bracket rod and a tension rod attached to said side walls adjacent their ends and extending across said block.

6. An anchor as in claim 5 and spaced webs extending 20 between said side walls with said tension rod extending across said webs at an opposite angle to the angle line of said anchor to the taper of said side walls.
